UNITED STATES PATENT OFFICE

BERT O. TILDEN, OF TRENTON, NEW JERSEY, ASSIGNOR TO B. O. T. MANUFACTURING COMPANY, OF TRENTON, NEW JERSEY, A CORPORATION OF NEW JERSEY

CONNECTION FOR WATER CLOSET COMBINATIONS

Application filed November 10, 1931. Serial No. 574,054.

This invention relates to a water closet combination comprising a bowl and tank, wherein the latter rests upon and is entirely supported by a rearwardly extending housing, in which the spur and other connections are disposed.

The primary object of the invention is to provide novel means for rigidly clamping the tank to the bowl, said securing means comprising similar clamping devices that pass through slotted openings in the bottom of the tank and also through registering openings in the deck of the housing, the bottom of the tank being formed interiorly with means for guarding and concealing parts of the clamping devices that are disposed within the tank and at the same time preventing the flushing water from escaping through said bottom openings. By the provision of the leak-preventing means, the several clamping devices may be applied to the tank bottom without any packings, and the said devices may be attached to the tanks by the manufacturer, thus facilitating the ready and quick assembling of the bowl and tank either before or during the installing of the combinations. And a further object is to provide clamping means of this class that may be applied and adjusted without tools, by simply manipulating the several parts of said securing means.

I attain these objects by the means set forth in the detailed description which follows and as illustrated in the accompanying drawing, in which—

Figure 1 is a top plan view of the water closet bowl, showing a rearwardly extending shelf, which is formed with a depending housing for the spud and other connections. Fig. 2 is a partial rear end elevation and a partial vertical cross-section, the latter taken on line 2—2 of Fig. 3, showing the internal construction and arrangement of the adjacent parts of the tank and bowl; also showing the several connecting means in position to rigidly clamp the tank to the bowl. Fig. 3 is a broken side-elevation of the bowl and tank. Fig. 4 is a horizontal section taken on line 4—4 of Fig. 2, showing the arrangement of the bottom of the tank, and the spud and other connections in the clamping positions. And

Fig. 5 is a broken vertical cross-section showing the clamping devices of Fig. 2 on an enlarged scale, also showing the mushroom shields to prevent the flushing water from escaping through the slots of the tank bottom.

In the drawing, 2 represents the closet bowl, which may be surmounted by an ordinary flushing rim, as 3, the latter being extended a considerable distance rearwardly of the bowl proper to form a shelf 3'. This extended portion is formed with a relatively large integral housing, as 3a, that lies below the plane of the shelf, the said housing having a relatively large opening 3b at its rear end, and the plane top of the shelf 3' being cut away to form a corresponding upwardly facing opening 3c to loosely receive the usual slip spud connections, as 4, that comprise a part of the flushing means, as best shown in Fig. 2. Within the housing 3a, is formed an integral hollow lip or spud support 5, that communicates for flushing purposes with the rim 3, as indicated by the dotted arrow in Fig. 3. The lip 5 has a plane top provided with a circular opening 5' that coincides with the opening 3c and receives the lower end of the connection 4. 6 represents the flush tank which may follow any of the usual constructions, whose bottom 6' is formed with a central discharge opening, as 6a, that aligns axially with the opening 5' of the lip and receives the top end of the connection 4, as shown in Fig. 2. In addition to the more or less stout and rigid slip connection 4, which tends, when tightened up, to draw and hold the tank in intimate contact with the shelf 3', the said shelf is provided with similar oblong longitudinal slots, as 3d, to receive bolts, as 7, that pass downwardly through registering oblong slots 6c that are formed in the bottom 6' of the tank, for rigidly and independently clamping the tank to the shelf 3'. By this arrangement, the spud connections are relieved of all dangerous strains and may be removed and replaced or adjusted without disturbing the bolts 7 and related parts. The top ends of the bolts 7 are formed with T-heads, as 7', that are slightly smaller than the slots 6c and are of greater length than the

breadth of said slots, so that when the heads 7 are inserted through the slots 6c and afterwards rotated a quarter turn, the heads assume a position at right angles to said slots (see Figs. 2, 4 and 5), and cannot be withdrawn from the tank until again brought into exact registry with the openings 6c. The bolts 7, in practice, are first applied to the bottom 6' of the tank in the manner last described, after which plain washers 8, split spring washers 8', and nuts 8a are fitted thereto and tightened up for rigidly holding the bolts against turning or being accidentally released from the tank. This work of applying the bolts 7 may be performed by the manufacturer of the tanks before the latter are shipped to the trade. To assemble the tanks and bowls as shown in Fig. 2, the plumber disposes the tanks above and clear of the shelf 3' and inserts projecting ends of the bolts 7 through the slots 3d of the shelf, and in doing so, the said washers and nuts are loosely disposed in the slots 3d. He next applies to the free ends of the bolts 7, which normally extend below the shelf 3', fiber or similar non-metallic washers 9, metal reinforcing plates 9' and finally wing-nuts 9a. These wing-nuts may be tightened sufficiently by hand to securely hold the tanks on the bowls, as shown.

In order to avoid all danger of leakage of the flushing water through the slots 6c, as well as to shield the clamping bolts 7 from injurious contact with the water, the bottom 6' of the tank is formed with hollow semi-spherical or mushroom-like guards 6d having a diameter greater than the length of the slots 6c, in which the heads of the bolts are disposed. This construction entirely eliminates all packing in connection with the said bolts and openings, and reduces the hazard of leakage to the single opening 6a that receives the spud connection 4. By referring to Figs. 2 and 5, it will be understood that the heads 7' of the bolts may be rotated freely within the guards 6d. By disposing the bolts 7 in line with the spud 4 and spacing these parts, as shown, affords a relatively broad clamping range which renders the combined bowl and tank practically as strong as though the outfit were cast en bloc.

The present clamping devices are extremely simple and strong, and may be readily and quickly applied and removed without the use of any tools, and besides, by the provision of the novel mushroom guards 6d, the bolts 7 require no packing. When the adjustable parts of the clamps are properly tightened, in order to effect the complete assembly of the tanks and bowls, the combination may be transported, installed or moved from one location to another, as one part. This cannot be done in the case of the older water closet outfit where the tanks are mounted upon the walls of the toilets and are only connected

with the bowls by the relatively delicate offset connections.

Having thus described my invention, what I claim is—

1. The combination with a water closet 70 bowl having a housing at its rear end, and a flush tank mounted upon the deck of said housing, said bowl and said tank having registering slots, of means for clamping the tank to the bowl comprising T-shaped bolts 75 adapted to extend downwardly through the bottom of the tank and said deck, nuts disposed in the slots of the housing to secure the bolts to the tank, and nuts engaging the bolts beneath the said deck to prevent separation of the tank and bowl.

2. The combination with a water closet bowl having a housing at its rear end formed with longitudinal slots, and a flush tank 85 mounted upon said housing, the bottom of said tank having openings that register with the slots in the housing, clamping devices adapted to extend downwardly through the corresponding slots of said bottom and the housing, said devices having T-heads to engage the top face of the bottom, threaded means interposed between the housing and the bottom of the tank to rigidly fasten the devices to said bottom, and threaded means 90 engaging the portions of the devices disposed inside of the housing to clamp and hold the tank in place.

3. The combination with a water closet bowl formed with a rearwardly extending shelf having upwardly facing slots, and a flush tank having a bottom formed with semi-spherical chambers projecting upwardly from the upper face of the bottom and with slots that communicate with said chambers, of screw bolts to clamp the tank to the bowl, said bolts having T-heads adapted to be inserted upwardly into the said chambers, the bodies of said bolts thence extending downwardly through said shelf, means to prevent the bolts from rotating in said chambers, and means carried by the bolts and engaging the bottom face of the shelf to clamp the tank to said shelf.

4. The combination with a flush tank having chambered portions cast on and projecting upwardly from the upper face of its bottom and having slots communicating with said chambers, and a water closet bowl having a shelf at its rear end formed with slots that register with the opening of the tank, of clamping devices adapted to extend downwardly through the bottom openings of the tank and said shelf, said devices having enlarged portions that are disposed in and shielded from the flushing water by said chambered portions, and which seat upon the upper face of the tank bottom means to secure said clamping devices to the bottom of the tank, and independent means to lock the 130

lower ends of said devices to said shelf and to draw the tank towards the shelf.

5. In combination with a water closet bowl having a rearwardly extending support provided with openings, a flush tank mounted upon said support and having a bottom formed with openings for registry with the openings of the support, clamping means extending through the openings and each having a part that seats upon the tank bottom, means disposed within the openings of the support to secure said clamping means to the tank, and means connected to the clamping means and engaged with the support beneath the latter to clamp the tank to the support.

6. In combination with a water closet bowl having a rearwardly extending support provided with openings, a flush tank mounted upon said support and having a bottom formed with openings for registry with the openings of the support, clamping means extending through the openings and each having a part that seats upon the tank bottom, hollow guards extending over and about the openings in the tank bottom to water-seal the latter and receiving said parts of the clamping means therein, means disposed within the openings of the support to secure said clamping means to the tank, and means connected to the clamping means and engaged with the support beneath the latter to clamp the tank to the support.

In testimony whereof I affix my signature.
BERT O. TILDEN.
